his Attorney.

UNITED STATES PATENT OFFICE.

MORRIS M. WERNER, OF ROXBURY, MASSACHUSETTS.

GARTER.

Application filed April 25, 1928. Serial No. 272,752.

This invention relates to improvements in garters or similar flexible elastic articles having resilient attachment against the skin of the wearer, and the invention has for its 5 principal object the provision of a garter having an underlying strip adapted to protect the body of the wearer from the elastic portion of the garter band, so that the skin will not be exposed to frictional contact with 10 the elastic portion and in order to prevent deterioration of the elastic material owing to the heat and moisture of the skin. Other objects reside in the novel construction and arrangement of the garter elements here- 15 inafter described.

A preferred embodiment of the invention is illustrated in the accompanying drawing, in which, Fig. 1 is a plan view of the improved garter; and Fig. 2 is a sectional detail taken on the line 2—2 of Fig. 1.

The garter comprises the usual fabric pad 1 having a depending stocking fastener 2 of any desired construction, a band adapted to incircle the leg and consisting of an elastic 25 portion 3 and a non-elastic fabric portion 4 suitably connected as by sewing at the thickened seam 5, and a flexible protective strip 6 of leather, fabric or other appropriate material attached to, or integral with, 30 the pad 1. The strip 6 extends under the elastic portion 3 and may have a loop 7 near its outer end through which the non-elastic fabric 4 may slide, to hold the strip 6 in proper position on the leg. The protective 35 strip should be of such length that it will underlie the elastic portion of the band when the elastic is fully extended, and the thickness of the seam 5 is preferably such that it cannot be pulled outwardly through the 40 loop 7.

The pad may have the usual stud 8 upon which the free end of the band may be fas-

tened by means of the loop or eye 9, but other types of clasps may be employed, if desired. The effective length of either or 45 both portions of the leg band may be adjusted by any usual means such as the sliders 10 to conform to the leg size of the wearer. The various portions of the garter may be colored or decorated, as desired, to 50 render the article attractive.

A garter constructed as thus described is simple and economical to manufacture and unusually comfortable and durable in use; owing to the provision of the protective pad 55 6 which prevents the elastic portion of the band from contacting with the skin of the wearer. The thickened seam 5 furnishes an effective stop or abutment adapted upon engagement with the loop 7 to limit the outward movement of the band; consequently 60 the elastic 3 cannot be unduly stretched, and cannot be pulled beyond the outer end of the protective pad to contact with the skin.

I claim:

A garter comprising a pad, a leg band 65 consisting of an elastic portion having one end connected to said pad and a fabric portion attached to the other end of the elastic portion, and a flexible, non-elastic strip 70 fixed at one end to said pad and extending beneath said elastic portion, said strip having a loop near its outer end through which the fabric portion may slide, the flexible strip underlying said elastic portion in use, 75 whereby contact between the leg of the wearer and the elastic is avoided, and a stop element formed at the juncture of said fabric and elastic portions adapted to engage said loop, thereby limiting stretching movement 80 of the elastic portion.

In testimony whereof I affix my signature.

MORRIS M. WERNER.
